United States Patent

Des. 235,590
Patented July 1, 1975

235,590

SPORT SHIRT

Vera Naumovski, 60 Roseland Drive,
Toronto, Ontario, Canada

Filed Mar. 2, 1973, Ser. No. 337,497

Term of patent 14 years

Int. Cl. D2—02

U.S. Cl. D2—208

FIG. 1

FIG. 2

FIG. 1 is a front elevational view of a sport shirt showing my new design, the back of the shirt being conventional, the sleeve cuffs showing a stitched design; and

FIG. 2 is a front elevational view thereof with the flap member in a second position.

I claim:

The ornamental design for a sport shirt, as shown and described.
